UNITED STATES PATENT OFFICE

JOHN J. MCINTYRE, OF HARTFORD, CONNECTICUT

METAL BALL GRINDING MACHINE

Application filed October 12, 1929. Serial No. 399,222.

This invention relates to a machine which is designed to receive roughly formed metallic balls and grind them to approximately finished size. A machine of this type is illustrated and described in Patent No. 1,527,808 granted to me February 24, 1925.

The object of the present invention is to simplify the construction and increase the efficiency of the prior machine, whereby the power required for operation is reduced, the life of the elements is lengthened, and the output is increased.

Broadly, this is attained by providing a circular metallic bed that is slowly rotated on one axis and an annular abrasive platen that is rapidly rotated in the same direction on an axis eccentric to that of the bed, the bed having a spiral ball-carrying groove into which the balls are automatically fed and from which they are automatically discharged after having been carried through the groove by, and subjected to the grinding action of the rapidly rotated eccentrically-mounted abrasive platen.

Fig. 1 shows a vertical section of the machine. Fig. 2 is a plan. Fig. 3 is a section looking down on the plane indicated by the dotted line 3—3 on Fig. 1. Fig. 4 is a diagrammatic view on larger scale of the bed and platen. Fig. 5 is a detail section on line 5 on Fig. 4.

The machine has a supporting frame 1, on top of which is an annular track 2. Rotatably mounted on this track is a disk 3 which is attached to the upper end of a vertical shaft 4 that is supported by bearings 5 at the upper part of the frame and bearings 6 at the lower part of the frame. This shaft has a worm wheel 7 which is engaged by a worm 8 on a horizontal shaft 9 that has a pulley 10 adapted to be belted to any convenient source of power.

Attached to the top of the disk 3 is a bed 11 that is desirably made of cast iron. The upper face of this bed is provided with a spiral ball carrying groove 12. The inner wall 13 of the inner coil of this groove is concentric with the axis of the bed, Fig. 4, and the outer coil 14 of the groove is also concentric with the axis of the bed, Fig. 4, and

slightly deeper than the rest of the groove, Fig. 5. At the beginning of the inner end of the groove is a wedge 34.

An annular grinding platen 15, which may be formed of emery, carborundum or a similar abrasive material, is fastened to the underside of flange 16 on the hub 17 which is secured to the lower end of a vertical shaft 18 that at its upper end has a pulley 19. This shaft is supported so that it may have a vertical movement, by bearings 20 in the bracket 21 that is mounted on the front of a column 22. The upper bearing is threaded at its lower end, and threaded on this is a sleeve 23 provided with radial pins 24 by means of which the sleeve may be turned. At the lower end of the sleeve is a flange 25 on which rests a collar 26 that is secured to the shaft. By screwing the sleeve up and down the shaft may be raised and lowered for adjusting the distance between the working faces of the grinding platen and the grooved bed. The axes of the platen and bed are eccentric, and the platen is designed to be rotated in one direction at high speed, for example approximately one thousand R. P. M., while the bed is designed to be rotated in the same direction at a much lower speed, for example five R. P. M.

The ball blanks are deposited in a hopper 27 located on the top of the frame and drop successively through a spout 28 into the innermost coil of the spiral groove in the bed. Loosely supported by and rotated with the platen is a plate 29 which is designed to prevent the balls from jumping out of the groove in the bed. This plate is fastened to the lower end of rods 30 which are loosely retained by the flange 16 and are connected at their upper ends with a ring 31.

The bed is rotated very slowly beneath the hopper feed spout and carries the balls which drop into the groove, beneath the under face of the rapidly rotating annular grinding platen, which, as the balls come within the sphere of action of the platen, advances the balls along the groove and at the same time effectively abrades them. As the axes of the bed and the platen are eccentric, the platen rotates on an arc from inside to out across

the path of the balls carried by the groove in the bed at one locality, and on an arc from outside to in across the path of the balls in the groove at another locality. By this means 5 the balls are subjected to the abrasive action of the grinding platen and adhesive rubbing of the walls of the bed groove, many times in the course of their travel from end to end of the groove, and are reduced to nearly the 10 finished size. After the balls have been carried completely through the groove they are ejected therefrom by the finger 32. A guard ring 33 is arranged about the bed to retain the balls in the outside coil of the groove until 15 they reach the desired delivery location. As the relation of the groove to platen is constantly changing, owing to the eccentricity of the platen and difference in speeds of rotation, the working face of the platen does not 20 become grooved, but wears down smoothly, which ensures a uniform accuracy of grinding of the balls.

The invention claimed is:

1. A ball grinding machine comprising a 25 rotatory metallic bed having a spiral groove in its face, mechanism for slowly rotating said bed, means for feeding balls into the inner end of said groove, means for directing balls out of the outer end of said groove, a rotatory abrasive platen capable of vertical movement toward the bed, the axis of said platen being eccentric with relation to the axis of the bed, and mechanism for rapidly 30 rotating said platen in the same direction as the rotation of the bed.

2. A ball grinding machine comprising a rotatory bed having a spiral groove in its upper face, mechanism for slowly rotating said bed, means for feeding balls into the inner 40 end of said groove, means for retaining balls in said groove, means for directing balls out of the outer end of said groove, a rotatory abrasive platen mounted above and capable of vertical movement toward the bed, the axis of said platen being eccentric with relation to the axis of the bed, and mechanism for rapidly 45 rotating said platen in the same direction as the bed.

JOHN J. MCINTYRE.
